UNITED STATES PATENT OFFICE

158,492

COUCH OR SIMILAR ARTICLE

James Mont, New York, N. Y.

Application October 29, 1948, Serial No. 149,393

Term of patent 3½ years

(Cl. D15—11)

To all whom it may concern:

Be it known that I, James Mont, a citizen of the United States of America, residing in New York, county of New York, and State of New York, have invented a new, original, and ornamental Design for a Couch or Similar Article, of which the following is a specification, reference being had to the accompanying drawing, forming part thereof.

Fig. 1 is a front perspective view of a couch or similar article showing my new design.

Fig. 2 is a rear perspective view thereof.

Fig. 3 is a top plan view.

Fig. 4 is an end view.

I claim:

The ornamental design for a couch or similar article, substantially as shown.

JAMES MONT.
